GRILL

Eugene Buday, Cheyenne, Wyo., assignor to Wyott Corporation, Cheyenne, Wyo., a corporation of Wyoming

Filed Nov. 19, 1965, Ser. No. 88,152

Term of patent 7 years

(Cl. D81—10)

Fig. 1

Fig. 3

Fig. 4

The left side of the grill has the same appearance as the right side thereof but reversed, and the rear of the grill is plain and unadorned.

I claim:

The ornamental design for a grill, as shown and described.
